A. C. GREENE

MARKER

Filed April 7, 1926

Inventor,
Albert C. Greene,
By Henry O. Cole atty

UNITED STATES PATENT OFFICE.

ALBERT CECIL GREENE, OF WILLESDEN JUNCTION, LONDON, ENGLAND.

MARKER.

Application filed April 7, 1926, Serial No. 100,356, and in Great Britain August 15, 1925.

This invention relates to improved means for producing a permanent, durable and visible mark or safety line for marking roads, in the middle or elsewhere in order 5 to guide or direct the drivers of vehicles or foot passengers and so on, and is intended more especially to prevent or diminish the liability to collisions between road vehicles travelling in opposite or different 10 directions and to avoid accidents to pedestrians and others. The invention is equally applicable for marking pavements in order to guide pedestrians and also for marking tennis courts and other places.

15 According to this invention, the improved means for marking roads and other places with a safety-line or other mark or marks comprises a number of strips or sections of metal or alloy or other durable material, 20 such as pottery, glass or artificial stone of a colour, such as white or black or some other colour, strongly contrasting with the colour of the surrounding material of which the road or other surface is made and incapable of becoming indistinct or darker 25 (or lighter as the case may be) than the surrounding road, pavement, tennis court or the like. Each of the strips or sections is furnished with a base or lower part or parts 30 adapted to be embedded, interlocked, keyed or anchored in the material of which the object such as the road surface or the road foundation is made. Preferably, each section is provided at each end with means 35 adapted to interlock, engage or be engaged with an adjoining strip or section. To cause adjoining sections to interlock, each section is, for example, provided with a concavity or female portion at one end and a 40 convexity or male portion to correspond at the other end. In order that the strips or sections may be securely anchored in the road, each strip is provided with sides or a single web and a flange or flanges or a lug 45 or lugs arranged to diverge. The sides, 50 preferably converge in a downward direction and are provided with outwardly extending lugs to assist the keying or anchoring of the strip in the road material or the like.

And in order that the invention may be easily understood and readily carried into

effect, reference will be made to the accompanying drawings, in which:—

Figure 1 is a perspective view of a section or strip for marking a road or other place and

Figure 2 is a section on the line II—II, Figure 1.

Figure 3 is a plan view showing how the strips are assembled in the surface of a road or the like.

Figures 4 and 5 are perspective views of modified forms of strips.

Figure 6 is a perspective view, taken from below, of a strip for forming an angle.

Figure 7 is a perspective view of another modification.

Figure 8 is a plan of a mould for containing several strips for reinforcement, filling and building up with concrete.

Figure 9 is a cross section on the line IX—IX of Figure 8, and

Fig. 10 shows another form of marker top.

On referring to Figures 1 and 2 of the drawing, it will be seen that the marking strip or device, suitably made of aluminium alloy or other appropriate material or metal, not readily oxidizable when in contact with air or moisture, is of inverted channel section, the bottom of the channel serving as the top *a* of the strip, forming the wearing surface flush with the road or other surface. The top *a* is flat or approximately flat, as are also the sides *b* which converge and each side is provided with an outwardly projecting flange *c*. Each of these strips or sections is provided at one end with a part-circular recess *d* and at the other end with a part-circular extension *e*. These strips are laid, for example as shown in Figure 3 end to end and interlocking on the concrete or other foundation of the road or are embedded in the road metal or other material in such a manner that the flat wearing surface *a* shall lie in the same plane as that of the surface of the road. The angles between the top *a* and the sides *b*, are, say, about 60° or 70° and the flanges *c* are about 90° to the sides. If made of aluminium alloy of good wearing qualities, it will be found that the safety-line, made up of a number of these strips, wears with the road. The dimensions and angles will be varied

according to requirements. In this example, the thickness of the top of each strip may be from one quarter to one half an inch throughout or the wearing surface may be 5 thicker than the other or keying parts, namely the converging sides *b* and the flanges *c*. The width of the wearing surface *a* is suitably four or five inches and each strip 10 may be a foot long or more. The depth of the strip with its sides is about two inches or more, according to the thickness of the asphalt or other road surface, the thickness of the sides is from one eighth to one quarter of an inch, and the flanges *c* are conveniently about one quarter of an inch or even 15 an inch wide, according to circumstances. If desired, the flat top portion *a* may be provided with a central narrow recess *f* extending for about two thirds of the total length 20 of the strip or the top *a*. This prevents wheels from slipping or skidding and also gives pedestrians a good foothold.

Figure 4 illustrates a strip very similar to that just described except that the central 25 portion is made chequered at *g* instead of recessed as in Figures 1 to 3 inclusive. The chequer-work serves to prevent slipping and if desired may extend over the whole top of the strip. This strip has sides and flanges 30 with gaps *j* in the sides and flanges to improve its keying qualities in the road metal, concrete or foundation.

In Figure 5, the recess is provided with a recess having cross bars *h*.

35 In Figure 6 the top *i* is curved at the right hand end and shaped at an angle of about 45° at the other end to connect with another strip at right angles thereto. In this construction, there are holes *k* instead 40 of a recess as in Figures 1, 2 and 3 or chequered work as in Figure 4 or a recess and bars *h* as in Figure 5.

Figure 2 illustrates a strip having its 45 upper edges provided with isolated recesses *n* of part-circular shape which in addition to preventing slipping or skidding of wheeled vehicles also enables the edges to wear more readily with the surface of the road and also forms a guide to show the 50 amount of wear which has taken place. Or the edges of the top may be chamfered or bevelled.

As in most cases, for road work, it is 55 advisable to anchor the strips in blocks of concrete, it will not be out of place to describe how this is conveniently effected and on referring to Figures 8 and 9, it will be seen that a mould is employed. This mould 60 comprises a bottom 3 to which one side 4 may be permanently fixed while the other side 5 is hinged at 6 and is, moreover, provided with fixed ends 7, of which only one is shown. The side 5 and ends 7 are temporarily secured to the side 4 by bolts such 65 as that marked 8 and fly nuts 9. Or other

suitable clamping means may be employed to hold the mould parts together during moulding and setting. To form a block 70 several strips are laid therein upside down as shown and between each adjoining two strips is inserted vertically a piece of sheet iron 10 (Figure 8) curved to the shape of the adjoining convex and concave ends of the strips and these pieces of sheet iron serve to separate each strip and its block 75 from its neighbour. The concrete aggregate and cement mixed are introduced into the mould and tamped down so that the concrete 80 fills all the space above and between the sides *b* and flanges *c* and the sides of the mould but not the spaces below the flanges *c* and between the sides *b* and the sides of the mould so that a span triangular in section is left between each lug *c*, the side *b* and the side of the mould. The result is a composite 85 block with a metal top *a*, converging metal sides *b*, with recesses 11 in the neighbourhood of the diverging flanges *c* and a concrete bottom corresponding to the upper 90 part of the mould. A trench is made in the road sufficiently deep to bring the top *a* of the strip flush with the road when the composite block is inserted therein and the block is grouted in.

In Figure 10 I have shown a modified form 95 of top section which is provided with converging sides and lateral flanges or lugs, as described with reference to the other forms herein. The section is formed part circular at each end to engage with two adjoining strips with part-circular recesses, or in case the strips are arranged isolated, or with spaces between them to save cost in marking the road or pavement. This strip may be 100 provided with a row of holes *k*.

105 Although the interlocking ends shown, are such as to allow of the strips being disposed more or less angularly to each other, it is evident that formations for the engaging ends may be other than curved but generally 110 it is found convenient for the interlocking ends to be part-circular as shown because this avoids the existence of acute angles and weak places or parts liable to be deformed by being struck by horseshoes or other hard 115 articles.

I claim:—

1. Means for producing a visible line for 120 marking the surface of the material of which roads and other places consist and comprising a plurality of strips of durable material of a colour contrasting with the colour of the material to be marked, each of the said strips consisting of a top, means on the upper surface of the top for preventing the 125 wheels of vehicles and the feet of human beings and animals from slipping thereon, converging sides extending downwardly from the said top, laterally extending flanges 130 projecting from the said sides, a male por-

tion at one end of the said strip, and a female portion at the other end of the said strip for enabling adjoining strips to interlock.

5 2. Means for producing a visible line for marking roads and other places, and comprising a plurality of strips of durable material of a colour contrasting with the colour of the material to be marked, each of the 10 said strips consisting of a top, converging sides, extending downwards from the said top gaps in the said sides, laterally extending lugs projecting from the said sides, a male portion at one end of the top of the 15 said strip and a female portion at the other end of the said strip for enabling adjoining strips to interlock.

3. Means for producing a visible line for marking roads and other places and comprising a plurality of strips of durable material and of a colour contrasting with the colour of the material to be marked, each of the 20 said strips consisting of a top, recesses along the upper edges of the top of the strip, 25 converging sides extending downwards from the said top, gaps in the said sides, laterally extending lugs projecting from the said sides, a male portion at one end of the top of the said strip and a female portion at the other 30 end of the top of the said strip for enabling adjoining strips to interlock.

4. Means for producing a visible line for marking roads and other places and comprising a plurality of strips of durable material and of a colour contrasting with the colour of the material to be marked, each of the 35 said strips recessed in the top to prevent slipping, recesses at intervals along the upper edges of the strip, converging sides extending downwards from the said top, gaps in the said sides, laterally extending lugs projecting from the said sides, a part-circular male portion extending at one end of the top of the said strip and a part-circular 40 recess at the other end of the top of the said strip for enabling adjoining strips to interlock.

5. Road or ground marker comprising a sheath composed of a top surface member 50 and longitudinal side members depending therefrom, said side members having a key formation adapted for taking grip when embedded in the ground, a block moulded on to said sheath so that part of said block 55 is contained within said sheath, the combined block and sheath being adapted for being embedded as a marker in a ground surface, a curved convex formation on one end of said block and sheath, and a curved concave 60 formation on the opposite end of said block and sheath, a series of these combined blocks and sheaths being adapted for being embedded end to end as a line marker in a ground surface, the curved end formations 65 providing interlocks between the said ends

and the key formations of the side members of said sheath being adapted for increasing the security of the anchoring of said marker in said ground surface.

6. A road or ground marker comprising 70 a rigid sheath composed of a surface member having a top to lie flush with the ground surface, longitudinal converging side members depending from each lateral edge of the said top and laterally projecting and 75 diverging lugs at the bottom of said side members, the said lateral lugs being located within the vertical planes including the longitudinal edges of the top.

7. A road or ground marker, comprising 80 a rigid sheath composed of a top member of which the upper surface is adapted to lie flush with the ground surface, means on the upper surface of the top for preventing the wheels of vehicles and the feet of human 85 beings and animals from slipping thereon, converging side members depending from each lateral edge of the said top and laterally extending flanges projecting outwardly from the bottom of the said sides, the said 90 converging sides and diverging flanges being located within the vertical planes including the longitudinal edges of the top and being adapted for securely anchoring the sheath when embedded in the material to be marked. 95

8. A road or ground marker, comprising a rigid sheath composed of a top of which the upper surface is adapted to lie flush with the ground surface, means on the upper surface of the top for preventing the wheels 100 of vehicles and the feet of human beings and animals from slipping thereon, converging side members depending from each lateral edge of the said top, laterally extending flanges projecting outwardly from the bottom of the said sides, and gaps in the said 105 side members and flanges, the said converging sides and diverging flanges being located within the vertical planes including the longitudinal edges of the top and being adapted 110 for securely anchoring the sheath when embedded in the material to be marked.

9. A road or ground marker comprising a rigid sheath composed of a top whose upper surface is adapted to lie flush with the ground 115 surface, means on the upper surface of the top for preventing the wheels of vehicles and the feet of human beings and animals from slipping thereon, converging side members depending from each lateral edge of the said top, notches at the angles of the top and sides, laterally extending flanges projecting outwardly from the bottom of the said sides, and gaps in the said side members and flanges, the said sides and flanges being located within the vertical planes including the sides of the top and being adapted for 120 securely anchoring the sheath when embedded in the material to be marked. 125

ALBERT CECIL GREENE.
